UNITED STATES PATENT OFFICE.

ELWOOD J. RODGERS, OF OMAHA, NEBRASKA.

SOUND-REPRODUCER.

1,359,467.

Specification of Letters Patent. Patented Nov. 16, 1920.

Application filed September 8, 1919. Serial No. 322,349.

To all whom it may concern:

Be it known that I, ELWOOD J. RODGERS, a citizen of the United States, and a resident of Omaha, in the county of Douglas and State of Nebraska, have invented certain new and useful Improvements in Sound-Reproducers, of which the following is a specification.

My invention relates to sound reproducing mechanism, and especially to reproducers adapted for use with disk sound-records having various types of record-grooves therein. It is the object of my invention to provide a sound-reproducer adaptable for use with each of the three common types of disk sound-records, namely (a) lateral-cut records, (b) vertical-cut records with rounded grooves, and (c) vertical-cut records having V-grooves; to provide in said reproducer a diaphragm and an appropriate stylus and stylus-lever for each of the several types of records above mentioned; to mount the multiple-diaphragm reproducer upon a single tone-arm and to provide means by which only the appropriate diaphragm-chamber will be placed in communication with the passage through the tone arm when the respective stylus is in position for engagement with the record; to so arrange the several styli and diaphragms that any of the styli may be disposed in a correct operative position by merely rotating the reproducer about an external portion of the tone-arm; and, in general, to provide a universal reproducer requiring a minimum of adjustment and of skill upon the part of the operator in order to correctly reproduce sound from records of any of the types mentioned.

In the accompanying drawings Figure 1 is a side view of mechanism embodying my invention, the reproducer being adjusted for use with the first above mentioned (a) type of records, Fig. 2 is a horizontal section on the line 2—2 of Fig. 1, Fig. 3 is a vertical section on the line 3—3 of Fig. 2, Fig. 4 is a detail vertical section on the line 4—4 of Fig. 2, Fig. 5 is a partial vertical axial section of the reproducer, as adjusted for use with records of the second above mentioned (b) type, Fig. 6 is a bottom view of the reproducer adjusted as in Fig. 5, Fig. 7 is a bottom view of the reproducer, as adjusted for use with records of the third above mentioned (c) type, and Fig. 8 is

a vertical axial section of the reproducer adjusted as in Fig. 7.

The reproducer mechanism provided by my invention is intended for use in connection with any suitable machine for rotating a sound-record disk at a controlled uniform speed, and having the usual sound-projecting or amplifying means, such machines being well known and having a horizontal rotary table A on which the record-disk is laid and centered, and over which the reproducer is traversed, the latter being carried by a horizontally swinging tone-arm which connects the sound-box with the horn or amplifying sound-conduit. In the structure shown I employ a tubular tone-arm 11 of the usual tapering form, the larger end thereof being turned downwardly and being pivotally connected with a fixed base 12 by any suitable means such that the horizontal portion of the arm may swing above the rotary table A, parallel therewith and to an extent such as to pass over the grooved portion of a record-disk upon the table. Near the outer or front end of the tone-arm 11, the same is turned laterally to form a hollow bearing-member 13 for a tubular arm 14, which is mounted thereon so as to be swingable in a vertical plane about said bearing-member. A circular port 15 in the front side of the bearing-member connects the passage through the tone-arm with that through the arm 14. As shown in Fig. 2, said arm is held upon the bearing by a washer 16 and a screw 17 which passes through the washer into the closed end of the hollow bearing-member. A cylindrical part 18, formed integrally with the arm 14, extends back from the bearing-member 13 substantially parallel with the main part of the tone-arm 11, and is filled, as shown in Figs. 2 and 8, with material 19 which forms a counterweight for the arm 14 and the multiple sound-box which is carried thereon.

The sound-box has a central tubular sleeve 20 which fits revolvably upon the tubular arm 14, and upon the intermediate portion of said sleeve there are three radially extending tubular portions or necks 30, 40 and 50, which are spaced equiangularly about the axis of the sleeve. The outer ends of said tubular portions or necks carry respectively the diaphragm-casings 31, 41 and 51, of which the outer faces are in planes spaced uniformly about the sleeve, as best shown in

Fig. 3. Within said casings are held the diaphragms 32, 42 and 52, the edges of the diaphragms being held between pairs of resilient rings 33, 43 and 53 disposed within the casings and retained therein by facing-rings 34, 44 and 54 which are secured to the casings by suitable screws.

In that side of the arm 14 which is nearest to the axis of the tone-arm 11 there is a circular port 21 which is adapted to register with the inner end of the opening through the necks 30, and in the lower side of said arm 14 there is a similar port 22 which is adapted to register with the openings through the necks 40 and 50 when the sound-box is rotated about the arm to the appropriate positions.

On the lower side of the counterweighting extension 18 a flat spring 23 is secured by means of screws 24, said spring being downwardly offset and extended forward as shown in Figs. 5 and 8, so that the free end portion thereof overlaps the rear end of the sleeve 20. An adjusting-screw 26, extending through the spring 23 as shown, enables the tension of said spring to be varied as desired. On the free end of the spring there is a rounded or semispherical projection 25 adapted to enter seats 35, 45 and 55 which are formed in the sleeve near the end thereof, and arranged circumferentially as shown in Fig. 4. The arrangement of the seats 35, 45 and 55 is such that when the part 25 enters the seat 35 the diaphragm 32 will extend vertically at the side of the arm 14 nearest the tone-arm 11, the opening through the neck 30 being in register with the port 21, and when the part 25 enters the seats 45 and 55, respectively, the diaphragms 42 and 52 will extend horizontally beneath the arm 14, and the openings through the necks 40 and 50 will be in register with the port 22.

Referring to Fig. 3 it will be seen that when the opening through one of the necks is in register with one of the ports 21 and 22, another of the neck-openings will be partially in register with the other of said ports. In order to provide for full closing of the last-mentioned port in each instance, a valve is provided within the bore of the arm 14, and means for actuating said valve automatically by rotation of the sound-box about the arm, as follows: The front portion of the arm is counterbored to a larger diameter than the portion adjoining the bearing-member 13, and in said counterbored portion there is slidably disposed the cup-shaped valve-body 27, the same having a port 28 in one side adapted to register with the port 21 in the arm 14 when the valve is in the rearward position shown in Fig. 2, and having in the lower side thereof a port 29 adapted to register with the port 22 when the valve is in the forward position shown

in Fig. 8. In the front end of the arm 14 a plate 60 is secured by means of screws 61, and said plate has a square central opening therein, through which a square rod 62 passes slidably. The rear or inner end of said rod 62 is threaded and screwed into the front end of the valve-body 27, and the front part of said rod 62 has a squared reduced portion 63 which extends through the end portion of a cup-shaped member 64. Adjoining the portion 63, the end of the rod is threaded and has screwed thereon a plate 65 which serves to fixedly retain the member 64 thereon. A coil spring 66 is disposed around the rod 62 within the arm 14, and tends to push the valve rearward to the position shown in Fig. 2. The outer or flange portion of the cup-shaped member 64 extends over the front end portion of the sleeve 20, and the rear edge of said flange portion is held by the spring 66 against a small roller 67 which is mounted on the sleeve as shown in Fig. 5. Said rear edge of the flange is cam-contoured, approximately one-half thereof extending parallel with the front face of the member, the remainder extending helically about the axis of the sleeve, and there being an abrupt offset or shoulder 68 extending back longitudinally of the sleeve from the front end of the helical portion, as best indicated in Figs. 5, 6 and 7. In changing the position of the sound-box upon the arm 14, the sleeve 20 is rotated in the direction of the arrow in Fig. 3, or clockwise as viewed from the front end of the arm. The cam-member 64 and the roller 67 are so arranged that in turning the sound-box about the arm 14 to the position shown in Figs. 1, 2 and 3, the roller will just pass the shoulder 68, and thus permit the cam and valve to be pushed rearward by the spring 66 to the position shown in Fig. 2, at which the roller will engage the helical cam-surface at the front end of said shoulder 68. By further rotation of the sound-box, to bring the same to the position shown in Figs. 5 and 6, the roller traverses the helical cam-face and pushes the cam-member and valve to the forward or second position thereof. Rotation of the sound-box from the last-named position to the position shown in Figs. 7 and 8 does not result in movement of the valve, as that part of the cam-face which is engaged by the roller is parallel with the path of movement of the latter. The square rod or valve-stem 62 serves, of course, to prevent any rotation of the valve and cam-member, and permits only longitudinal sliding movement thereof.

A suitable stylus-lever 36 has one end thereof connected with the center of the diaphragm 32 and is pivoted between lugs 37 on the facing-ring 34, the outer end of said lever having formed therein a socket for receiving removably a stylus 38 which

is retained in the socket by means of a screw 39. Said stylus-lever 36 is so arranged that when the diaphragm 32 is in the vertical position shown in Figs. 1, 2 and 3, the lever 5 and stylus will extend diagonally forward and downward, as indicated, the stylus thus being in proper operative position for use with a lateral-cut record V on the table A.

To the center of the diaphragm 42 there is connected one end of a stylus-lever 46, said lever being pivoted between lugs 47 on the facing-ring 44, the outer or forward portion of the lever extending out angularly from the face of the diaphragm and having a socket for receiving a removable stylus 48 which is retained in the socket by a screw 49. Said stylus-lever 46 is so arranged that when the diaphragm 42 is in the horizontal position shown in Figs. 5 and 6 the stylus 0 will be in proper operative position for use with a vertical-cut record P on the table A. The stylus 48 is preferably of the permanent ball-pointed type customarily used with vertical-cut records having rounded grooves, and with which it is desirable that the stylus engage the record at an angular position as shown in Fig. 5.

To the diaphragm 52 there is connected one end of a stylus-lever 56 which is pivoted between lugs 57 on the facing-ring 54, the outer or front end-portion of the lever being turned out substantially at right angles to the plane of the diaphragm and having a socket formed therein for receiving a stylus 58 which is retained in the socket by means of a screw 59. Said stylus-lever 56 is so arranged that when the diaphragm 52 is in the horizontal position shown in Figs. 7 and 8 the stylus 58 will be in proper operative position for use with a vertical-cut record E on the table A. The stylus 58 is preferably of the type having a permanent V-point of diamond or like hard material, such as is commonly used for vertical-cut records having V-shaped grooves, and with which it is desirable that the stylus extend substantially perpendicular to the face of the record, as shown in Fig. 8.

The general arrangement of the parts is such that when each stylus is in operative position the point thereof is at a distance from the vertical pivotal axis of the tone-arm 11 such that in traversing the record the stylus-point moves in an arc intersecting the center of the table A. Each stylus thus moves across the grooved part of a record upon a path which is nearly radial thereto, and in conformity with the path of movement of the recording stylus used in producing the original or master records. It will also be noted that each stylus-lever is so arranged that when in operative position it will lie substantially in a plane extending through the pivotal axis of the tone-arm, and tangent to the record-groove at the

point engaged by the stylus. This is effected by disposing the levers 46 and 56 at a slight angle to the axis of the sleeve 20, as shown in Figs. 6 and 7, and by so proportioning the parts that the lateral offset of 70 the lever 36 from the axis of the sleeve 20 is enough to bring said lever substantially into alignment with the tone-arm 11, when viewed as in Fig. 2.

Thus it will be seen that my invention 75 provides reproducing mechanism for each of the described classes or types of sound-records, each group of the mechanism having its own diaphragm, stylus-lever and stylus; the styli being of the proper form and material, arranged to engage the record at the correct angle, and to traverse the record in the desired way. It will also be seen that, by the arrangement of the several diaphragm-casings in the manner described to 80 form the multiple sound-box, and by the use of the automatically controlled valve 27, the only operation required, in adjusting the instrument for use with a sound-record of any class, is the mere rotation of the 85 multiple sound-box about the arm 14 until the proper stylus is in position to engage the record. I am thus able to dispense with such operations as changing styli, varying the length of the tone-arm, varying the position of a stylus-lever relatively to the sound-box, or adjusting of counterweights, in adapting the instrument for use with the different classes of records. In this connection I will call attention to the fact that 90 the variations in longitudinal position of the valve-parts 27, 62, 64 and 65, in changing from lateral-cut to vertical-cut records, causes the stylus-pressure to be automatically increased for the latter class of records 95 and reduced for the first-named class. It will be apparent that, by suitably proportioning the longitudinally movable parts, the variations of stylus-pressure may be made as great or as little as desired. 100

Now, having described my invention, what I claim and desire to secure by Letters Patent is:

1. In a sound-reproducing mechanism, a tubular swingable arm having a plurality of lateral openings therein, a multiple sound-box fitting revolvably on said arm and having diaphragm-chambers communicating with passages extending in to the arm and adapted to register with the lateral openings 115 therein, a valve for closing said openings selectively, and means actuated by rotation of the sound-box for controlling said valve. 120

2. In a sound-reproducing mechanism, a multiple sound-box comprising a tubular sleeve, a plurality of tubular necks extending radially therefrom, and diaphragm-casings carried at the outer ends of said necks; a tubular arm upon which said sleeve is fitted revolvably, said arm having ports 130

adapted to register with the openings through the necks of the sound-box, and a member slidable longitudinally of the arm to open and close the ports therein.

- 5 3. In a sound-reproducing mechanism, a multiple sound-box comprising a tubular sleeve, a plurality of tubular necks extending radially therefrom, and diaphragm-casings carried at the outer ends of said necks;
- 10 10 a tubular arm upon which said sleeve is fitted revolubly, said arm having in the sides thereof a plurality of ports adapted to register with the openings through the necks of the sound-box, a valve-member slidable longitudinally within the bore of the arm and having ports movable into and out of register with the ports in the arm, a cam-member connected with said valve-member, and means on the sound-box sleeve engageable
- 15 15 20 with said cam-member to move the valve during rotation of the sound-box about the arm.
- 20 4. In a sound-reproducing mechanism, a horizontally swingable tone-arm, a tubular arm pivoted on said tone-arm and swingable vertically, a multiple sound-box fitting revolubly on said tubular arm, said sound-box having a plurality of diaphragms and associated stylus-levers and styli, the several styli being movable to operative position solely by rotation of the sound-box about the tubular arm, there being separate diaphragm-chambers for each of said diaphragms, means forming passages for connecting the several diaphragm-chambers with the passage through the tubular arm when the respective diaphragms are in operative position, and means controlled by

rotation of the sound-box for closing the passages between the tone-arm and the diaphragm-chambers of the parts not in operative position.

5. A structure as set forth in claim 4, wherein the passage-closing means comprise parts movable longitudinally of the tubular arm to vary the effective weight upon that stylus which is in operative position.

6. A structure as set forth in claim 4, wherein the passage-closing means comprise a valve movable within the tubular arm, and a cam-member connected with said valve and engageable with a part upon the sound-box to be actuated thereby during rotation of the sound-box.

7. In a sound-reproducing mechanism, the combination with a multiple sound-box having a plurality of diaphragms and diaphragm-chambers with passages extending toward a common center, and a tubular arm upon which the sound-box is mounted revolubly, the arm having lateral ports adapted to register with the passages to the diaphragm-chambers at determined positions of the sound-box; of a valve slidable longitudinally within the tubular arm and having ports adapted to register consecutively with the ports in the arm, a spring pressing said valve yieldingly to one position, a cam-member connected fixedly with the valve, and a part carried upon the sound-box and engaging the cam-member to move the same in opposition to said spring during a part of the rotation of the sound-box about the tubular arm.

E. J. RODGERS.
